Primary Examiner — Janice Patyk*Assistant Examiner* — Ji Sun Yoon(74) *Attorney, Agent, or Firm* — Schacht Law Office, Inc.; Michael R. Schacht(57) **CLAIM**

The ornamental design for a beverage container holder, as shown and described.

DESCRIPTION

FIG. 1 is a top perspective view of a beverage container holder showing my new design;

FIG. 2 is a bottom perspective view thereof;

FIG. 3 is a front elevation view thereof;

FIG. 4 is a first side elevation view thereof;

FIG. 5 is a second side view elevation view thereof;

FIG. 6 is a rear elevation view thereof;

FIG. 7 is a top plan view thereof; and,

FIG. 8 is a bottom plan view thereof.
